UNITED STATES PATENT OFFICE.

MERTON E. JOHNSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

SOLE.

1,393,688.

Specification of Letters Patent.

Patented Oct. 11, 1921.

Application filed October 30, 1919. Serial No. 334,399.

To all whom it may concern:

Be it known that I, MERTON E. JOHNSON, a citizen of the United States, residing at Beverly, in the county of Essex and State 5 of Massachusetts, have invented certain new and useful Improvements in Soles; and I do hereby declare the following to be a full, clear, and exact description of the invention, such as will enable others skilled 10 in the art to which it appertains to make and use the same.

This invention relates to soles and more particularly to soles of the peaked toe type employed in the manufacture of the prevailing 15 styles of pointed toe shoes.

The narrow space at the apex of the channel on a peaked toe insole, or turn sole, makes it difficult for the operator of the in-seaming machine to force the sole around 20 the channel guide when swinging the sole at the toe. Relief from this condition has been obtained by slitting the channel flap transversely at the point of the toe, thus permitting it to lift and afford a freer movement 25 for the channel guide. A machine for producing this slit is disclosed in Letters Patent of the United States to John B. Hadaway No. 1,087,578, dated February 17, 1914. It has been found, however, that the channel 30 guide has a tendency to pass through such a slit instead of passing beneath it and so beneath the channel flap at the other side of the sole.

One object of the present invention is to 35 overcome this disadvantage in the sole produced by the toe snipping machine described in said Hadaway patent. To this end the character of the cut through the channel flap is materially changed and is so shaped and 40 located as to provide for the free swinging of the sole and yet prevent the channel guide from slipping out from beneath the flap.

The machine of said Hadaway patent, for 45 welt insole work, produces a V-shaped notch in the lip, this notch being centrally located at the tip of the toe. In the later operation of turning and setting the lip, by a machine, for example, of the type disclosed in Letters Patent of the United States to Albert E. 50 Johnson No. 1,252,348, dated January 1, 1918, the lip at the toe of an insole produced by the machine of the Hadaway patent is badly distorted and misplaced because of the fact that the opposed action of the tools

engaging the lip and the feeding mechanism 55 engaging the sole exert a continuous forward drag on the lip causing it, being the weaker element, to creep toward the toe at one side and toward the heel at the other.

Another object of the present invention is 60 to provide an insole fitting which will overcome defects in the lip at the point of the toe thus eliminating cripples from the cause referred to. Accordingly it is proposed to so shape and locate the lip cut at the tip 65 of the toe as to compensate for the advance or creeping of the lip during the lip setting operation and thus obtain a properly set lip about the toe.

To the accomplishment of these objects the 70 invention comprises a sole having the features and characteristics hereinafter described and the method of making it, as particularly pointed out in the appended claims.

The accompanying drawings illustrate the 75 preferred fitting to be used, Figure 1 illustrating the shape and location of the new lip and flap knives which may be incorporated in the machine of said Hadaway patent; Fig. 2 illustrating the forepart of a 80 sole blank after having been operated on by the knives shown in Fig. 1; and Fig. 3 illustrating an insole fitted as in Fig. 2 with the lip and channel formed and the lip set.

In the embodiment of the invention illustrated in the drawings the sole blank is fitted with two incisions 4 and 6, the former 85 extending through the lip material and the latter through the channel flap material. The incision 4 is formed by a knife 8 having 90 two blades 7 and 9 which produce the legs of a right-angular cut, and the incision 6 is formed by a knife 10 which has a blade 11 of general U-form in outline. When fitting a sole blank in the manner hereinafter 95 described the knives are so located relative to each other and the blank is so positioned beneath the knives by gages for that purpose, that the knife 8 makes its incision off-center, at the extreme point of the toe, while the 100 knife 10 makes its incision at the rear thereof with the base of its U directed toward the toe. Viewing the sole blank from the heel toward the toe, the blade 7 of the knife 8 incises the blank substantially on the 105 median line of the forepart, preferably although not necessarily slightly to the right thereof, and the blade 9 incises to the edge

of the blank at the left thereof. The heel of the knife 8 shaves the outer edge of the between-substance material. The knife 10 produces a U-shaped incision 6 centrally of 5 the blank symmetrically placed with relation to median line of the forepart, but with the base of the U somewhat farther from the incision 4 than the thickness of the usual between-substance. In other words, the 10 heel of the knife 10 is spaced a short distance to the rear of the inner edge of the between-substance material but not so far therefrom as to clear the channel flap material. The preferred shape and location 15 of the incisions is clearly indicated in Fig. 2.

The incised sole blank may be taken directly to the machine of said Johnson patent for the combined channeling and lip setting operation. The result of this operation is 20 illustrated in Fig. 3 wherein it is observed that the channel knife in passing through the U-shaped incision 6 removes the portion of the channel flap which lies within the U and forward of the inner boundary 12 of the 25 channel cut at the apex of the channel. This opens up the channel at the narrowest portion and permits the channel guide of the inseaming machine to pass freely from one side of the sole to the other. At the same 30 time, because the base of the U-shaped incision 6 does not reach forward to the between-substance, a portion of the channel flap at the apex thereof remains intact and forms a continuous ledge beneath which the 35 channel guide is guided and prevented from leaving the channel.

In lifting and setting the lip by the machine of the Johnson patent, the lip on the first side of the sole operated on is drawn 40 or crowded toward the toe, this action being indicated at 13 (Fig. 3) and as a result the straight edge formed on the lip by the blade 9 is thrown somewhat forward (illustrated by dotted line 14) so that when it has been 45 set it lies substantially on the center of the toe. On the other hand, the second side of the sole operated on has its lip drawn or crowded toward the heel, this action being indicated at 15 (Fig. 3), and consequently 50 the straight edge formed on the lip by the blade 7 is thrown backward somewhat (indicated by dotted line 16), so that when it has been set it also lies substantially on the center of the toe. The action is such that 55 the two edges meet and abut in the center at 17 (Fig. 3) causing the lip to lie smoothly about the toe and thus retaining the desired shape of the lip and maintaining the outline of the toe portion of the shoe when the upper 60 and welt are secured thereto.

It is particularly pointed out that the U-shaped cut is a valuable feature in soles which are not provided with a lip, for example turn soles or insoles for women's work, 65 hence this feature of the invention is not de-

pendent on the presence of the V-shaped lip incision. Similarly the lip incision may be employed with other forms of knives for making the channel flap incision. Furthermore, those skilled in the art will understand 70 that in making the sole, in so far as the channel flap incision is concerned, it is immaterial whether the sole is incised before or after the channel is formed.

The particular shape of the flap knife is 75 a matter to be determined by the style of the sole to be operated upon. The flap knife illustrated in Fig. 1 is capable of general use but is especially adapted to medium pointed toes. For extreme peaked toes it is 80 often desirable to employ a flap knife of V-shape, and for turn soles excellent results have been obtained with a flap knife having two parallel blades joined by a blunt V, instead of a semi-circular connection, at their 85 forward ends. It will be observed that all the flap knives for the special types of soles referred to embody two legs which are joined at one end and, therefore, they all may be defined by the expression "of general 90 U form." When this expression occurs in the appended claims it will be understood as inclusive of any type of incision in the channel flap material which produces a rearwardly opening notch in the flap, irrespec- 95 tive of the particular shape of the notch.

The nature and scope of the present invention having been indicated and the preferred embodiment of the invention having been specifically described, what is claimed 100 as new, is:—

1. A sole having an incision of general U form through the channel flap material the legs of which intersect the inner edge of said material, located centrally within the 105 margin at the toe.

2. A sole having an incision of general U form located centrally within the margin at the toe with its heel spaced to the rear of the between-substance material a distance 110 less than the width of the channel flap.

3. A sole having an incision of general U form through the channel flap material at the apex of the channel, the base of the U being directed toward the toe of the sole. 115

4. A sole provided with a channel flap having a portion of general U form removed from the apex thereof.

5. A sole provided with a channel flap having a rearwardly opening notch at the 120 apex thereof extending only part way through the width of the flap.

6. An insole having an incision of general V form through the lip material at the tip of the toe, one leg thereof substantially coinciding with the median line of the forepart of the insole and the other leg thereof lying substantially at right angles to said median line. 125

7. An insole having an incision of general 130

- V form through the lip material at the tip of the toe, its apex abutting the outer edge of the between-substance material, and the lip material between its legs lying to the left, 5 viewing the insole from heel to toe, of the median line of the forepart of the insole.
8. The method of making soles which includes the steps of incising the channel flap material at its apex by a cut of general U- 10 form symmetrically arranged with relation to the median line of the forepart of the sole with its heel directed toward the toe, and producing a channel cut, said two cuts intersecting to provide a rearwardly opening 15 notch in the channel flap.
9. The method of making insoles comprising incising a sole blank at the tip of the toe by a V-shaped cut having one leg substantially on the median line of the fore- 20 part of the insole and its other leg extending to the left thereof, viewing the blank from heel to toe, and then edge slitting the blank
- through said incision and setting the lip thus produced by tools which displace the edges formed by the V-shaped cut in a manner to cause them to abut, after the setting operation, substantially on the center of the toe. 25
10. The method of making insoles comprising incising a sole blank at the tip of the toe by a right angular cut having its heel at the outer edge of the between-substance material, one leg substantially on the median line of the forepart of the insole and its other leg extending to the edge of the sole at the left 30 thereof, viewing the blank from heel to toe, then edge slitting the blank through said incision and, while simultaneously setting the lip, drawing or crowding the lip thus produced forward on the first side of the insole thus slit and rearward on the other side 35 of the insole. 40
